Robert O. Ernest, Oak Park, Ill., assignor to Sunbeam Corporation, Chicago, Ill., a corporation of Illinois

Application April 16, 1958, Serial No. 50,498

Term of patent 14 years

(Cl. D9—2)

Fig. 1 is a perspective view of a floor polisher showing my new design;

Fig. 2 is a side elevational view thereof;

Fig. 3 is an enlarged front elevational view thereof with the handle fragmentarily shown for convenience of illustration only;

Fig. 4 is an enlarged top plan view thereof as shown in Fig. 3; and

Fig. 5 is an enlarged side elevation thereof as shown in Fig. 3.

The dominant features of my design reside in the portions shown in full lines.

I claim:

The ornamental design for a floor polisher or similar article, substantially as shown and described.
